US00D737650S

(12) **United States Design Patent**
Allen et al.

(10) **Patent No.:** US D737,650 S
(45) **Date of Patent:** ** Sep. 1, 2015

(54) **UTILITY BAR**

(71) Applicant: **Milwaukee Electric Tool Corporation**,
Brookfield, WI (US)

(72) Inventors: **Joel Allen**, Winton, CA (US); **Mark R. Martinez**, Atwater, CA (US); **Timothy Albrecht**, Menomonee Falls, WI (US)

(73) Assignee: **Milwaukee Electric Tool Corporation**,
Brookfield, WI (US)

(**) Term: **14 Years**

(21) Appl. No.: **29/477,978**

(22) Filed: **Dec. 30, 2013**

Related U.S. Application Data

(63) Continuation of application No. 13/683,956, filed on Nov. 21, 2012, now Pat. No. 8,646,138, which is a continuation of application No. 12/614,071, filed on Nov. 6, 2009, now Pat. No. 8,365,332.

(57) **CLAIM**

We claim the ornamental design for a utility bar, as shown and described.

DESCRIPTION

FIG. 1 is a perspective view of a utility bar.

FIG. 2 is a left side view of the utility bar shown in FIG. 1.

FIG. 3 is a right side view of the utility bar shown in FIG. 1.

FIG. 4 is a front view of the utility bar shown in FIG. 1.

FIG. 5 is a rear view of the utility bar shown in FIG. 1.

FIG. 6 is a top view of the utility bar shown in FIG. 1; and,

FIG. 7 is a bottom view of the utility bar shown in FIG. 1.

Any showing of the environment by broken lines having equal length segments depicts environmental subject matter only and forms no part of the claimed design.

1 Claim, 4 Drawing Sheets
